United States Patent Office

Des. 215,209
Patented Sept. 16, 1969

215,209

WHEEL COVER

Joel A. Anderson, River Forest, Ill., assignor to Namsco,
Inc., Bellwood, Ill., a corporation of Illinois

Filed July 10, 1968, Ser. No. 12,674

Term of patent 3½ years

Int. Cl. D12—14

U.S. Cl. D14—30

FIG. 1 is a perspective front view of the wheel cover embodying my new design;

FIG. 2 is an enlarged front elevational view of the wheel cover of FIG. 1;

FIG. 3 is a bottom view of FIG. 2; and

FIGS. 4 and 5 are enlarged fragmentary sectional views taken along lines 4-4 and 5-5, respectively, of FIG. 2.

I claim:

The ornamental design for a wheel cover, substantially as shown.
